UNITED STATES PATENT OFFICE

168,801

HOBBYHORSE

Burton L. Murray, Colton, Raymond A. Tefft,
Beaumont, and Lindsy L. Hubby, San Bernar-
dino, Calif.

Application August 5, 1952, Serial No. 20,896

Term of patent 14 years

(Cl. D34—15)

To all whom it may concern:

Be it known that we, Burton L. Murray, Raymond A. Tefft, and Lindsy L. Hubby, citizens of the United States, residing respectively at Colton, in the county of San Bernardino; Beaumont, in the county of Riverside; and San Bernardino, in the county of San Bernardino, all in the State of California, have invented a new, original, and ornamental Design for a Hobbyhorse, of which the following is a specification, reference being had to the accompanying drawing, forming a part hereof.

Figure 1 represents a side elevation of a hobbyhorse embodying our new design;

Figure 2, a front elevation thereof; and

Figure 3, a top plan view thereof.

We claim:

The ornamental design for a hobbyhorse, substantially as shown.

BURTON L. MURRAY.
RAYMOND A. TEFFT.
LINDSY L. HUBBY.
